UNITED STATES PATENT OFFICE.

ERNEST KOHLER, OF DENVER, COLORADO, ASSIGNOR TO THE UNITED MINES AND MANUFACTURING COMPANY, A CORPORATION OF ARIZONA.

AMUSEMENT DEVICE (CIRCLING WHIP.)

1,398,639.

Specification of Letters Patent. Patented Nov. 29, 1921.

Application filed August 28, 1919. Serial No. 320,392.

To all whom it may concern:

Be it known that I, ERNEST KOHLER, a citizen of the United States, residing at Denver, in the county of Denver and State 5 of Colorado, have invented certain new and useful Improvements in Amusement Devices, (Circling Whip;) and I do hereby declare the following to be a full, clear, and exact description of the invention, such as 10 will enable others skilled in the art to which it appertains to make and use the same.

This invention relates to amusement apparatus and especially to the form of apparatus in which there are provided independent carriages or cars which are each anchored pivotally to a suitable structure between which and another or other supporting table structures relative circular or other suitable movement is produced so that 20 the carriages or vehicles are caused to travel in erratic and indeterminate paths of movements while at the same time being subjected, if desired, to a course of travel in a generally circular orbit.

It is one of the objects of the present invention to provide an apparatus which will not only be attractive as an amusement but which will at the same time provide for the necessary degree of safety and which further 30 may be operated at an economical cost in consumption of power and which may be operated with a minimum of personal attendants. A further object of the invention is to provide an apparatus of this type which 35 will include passenger cars or carriages which may be in a measure subjected to the control of the passengers or entirely independent thereof. A further object of the invention is to provide an apparatus of this 40 kind which, while providing an innocent and very entertaining form of amusement yet can be constructed inexpensively and may be easily repaired in exigencies.

With the above and other objects in view 45 as will become apparent to those versed in the art from the following description the invention consists of the construction, the combination, and in details and arrangements of the parts as shown in the accompanying drawings wherein:

Figure 1 is a plan view of the apparatus.

Fig. 2 is a vertical, diametrical section of the apparatus.

Fig. 3 is a plan view of the driven annulus

and the means for driving and supporting 55 the same.

Fig. 4 is a transverse, sectional view showing in detail a portion of the annulus with its driving and supporting means.

Fig. 5 is a transverse, sectional view 60 through the annulus showing a modified form of support.

Fig. 6 is a vertical, sectional view through one form of the car or carriage in which there is provided a hand wheel by which some of 65 the motions of the car can be controlled.

Fig. 7 is a plan view of one type of truck for the car and

Fig. 8 shows a modified form of the car mounted upon its truck. 70

In the illustrated embodiment of the invention there is shown an annular and relatively wide floor or table 2 of suitable dimensions and style of construction the general surface of which is plane but which has 75 at different points and at suitable locations therein diverse forms of irregularities as spherical protuberances 3 and other various projections as in the form of the conic areas which may be concaved or convexed as 80 shown clearly at 4 and 4' in Fig. 2. Approximately fitting within the inner circle of this outer floor or table 2 there is an annulus or driving ring 5 of suitable form of construction and dimensions, its upper surface lying flush with and forming a continuation of the general floor surface and within the circle of this annulus there is a circular floor or table 6 the surface of which 85 also may be of various contour as for instance plane in portions and concave and convex in different portions. 90

To secure the desired results in this present apparatus the annulus 5 is the driven member, though it is obvious that this member might be stationary and the outer and inner tables 2 and 6 may be rotated with respect to the annulus 5. 95

At suitable spaces or points around the annulus or driven ring 5 are placed anchors 100 or pivot pins or fastening means 7 to which are connected the tongues 8 of trucks consisting of transverse bars 9 to which the tongues 8 are attached. Each of the trucks has at the outer ends of its bar 9 caster 105 wheels or rollers 10 designed to run over and bear upon the track or surfaceway of the organized elements 2, 6 and 5. Upon

each of the trucks there is mounted a suitable form of carriage or vehicle 11, in Fig. 6 the vehicle being shown as supported upon a set of antifriction bearings 12 at 5 the center of truck bar so that the car 11 can rotate about a vertical axis independently of the movement of the truck. In Fig. 8 the car body is shown as rigid with the truck structure. To enhance the amusement feature of the apparatus the cars 11 10 may be provided if preferred, each with a central wheel 12' to be grasped by the occupants of the car either for the purpose of allowing them to steady themselves during 15 the operation of the apparatus when the car is being drawn along by the truck or to lead them into the belief that motion of the car can be controlled through means of the steering wheel, it being possible of course 20 that some very slight control may be effected by the occupants of the car grasping the wheel 12' to overcome centrifugal motion or the inertia of the car.

A suitable form of driving means may 25 be utilized to drive the relatively movable structures and in Fig. 4 the annulus 5 is shown as provided on its outer circumferential face with a groove 5^a in which there runs a cable 15 leading off from one side 30 of the annulus and being guided around a suitable guide and tension pulleys 16; a bight of the cable 15 being wound around a drum 17 geared to the shaft of the motor 18, all of which may be concealed beneath 35 the outer table or floor structure 2. The annulus which is shown in Fig. 4 has a rectangular cross-section, is supported on horizontal rollers 20 and also supported by vertical rollers 21 bearing against the inner 40 circular surface of the annulus 5.

A slightly modified form of supporting rollers is shown in Fig. 5 in which case each horizontal roller 20 is provided with a circumferential groove 20^a to take a downwardly projecting rib or fin 5^b formed on 45 or attached to the bottom surface of the annulus 5. In the case of the use of vertical rollers 21 as in Fig. 4 these may be adjusted readily with respect to their bearing 50 surface by suitable adjusting bearings 22.

It is obvious that various modifications, alterations and changes in details of construction and method of operation may be resorted to within the spirit of my invention 55 and scope of the annexed claims.

The operation of the apparatus is substantially as follows: Assuming that the annulus 5 is the driven member it will be seen that centrifugal action will cause the 60 cars or carriages 11 to swing outwardly as tongues 8 pivot about their anchors or pivots 7 and in this outwardly swinging action the wheels of the trucks will be caused to roll over the undulating or irregular 65 surface of the table structure 2 at certain

points and at others will be thrown inwardly to ride on the circular table or floor 6 and engage the irregular surfaces of the same. If the bodies of the cars be mounted pivotally on the trucks 9 it will be seen that 70 there can also be a free movement of the body with respect to the trucks further enhancing the peculiar and indeterminate movements of the vehicles as they are thrown around by the driven annulus. Occupants of the cars when they are provided with the hand wheels 12', may attempt to control the movement of the car by grasping these wheels and also may control their own positions in the cars by grasping the 80 wheels which latter will form a support to enable the occupants to steady themselves in the cars.

The wheel 12' can also be used as a steering wheel when it is fastened to the truck 85 as shown in the drawing.

Having thus described my invention what I desire to claim is:

1. In an amusement apparatus of the character described, an inner and outer concentric supporting structure spaced from each other at their adjacent edges and having a generally horizontal top contour; an intermediate member arranged in and bridging said space; and a car having wheels to 90 traverse the surface of the said inner and outer concentric supporting structures and said intermediate member, said car having a tongue pivotally connected to said member, the latter and said concentric supporting 95 structures having relative circular movement so that the car may be indefinitely trailed to and fro over the surfaces.

2. In an amusement apparatus of the character described, an inner and outer concentric supporting structure spaced from each other at their adjacent edges and having a generally horizontal top contour; an intermediate member arranged in and bridging said space; and a car having wheels to 105 traverse the surface of said inner and outer concentric supporting structures and of said intermediate member, said car having a tongue pivotally connected to said member, the latter and said concentric supporting 110 structures having relative circular movement so that the car may be indefinitely trailed to and fro over the surfaces, and means for rotating the member to which the 115 cars are connected.

3. In an apparatus of the character described, an inner supporting table having a generally horizontal top area provided with irregularities; an annulus surrounding said inner table; an outer annular table of generally horizontal top contour, the inner edge 125 of said outer table being disposed in close juxtaposition to said annulus; and a car having a wheeled truck, which car is pivotally connected to the annulus at spaced in- 130

5 tervals and which is adapted to sweep over the general top plane of the structure while relative rotary movement is imparted as between the annulus and the supporting tables.

4. In an apparatus of the character described, an inner supporting table having a generally horizontal top area provided with irregularities; an annulus operating around

10 the inner supporting table; an outer annular table of generally horizontal top contour, the inner edge of said outer table being disposed in close juxtaposition to said annulus; and a car having a wheeled truck, which car

15 is pivotally connected to the annulus and which is adapted to sweep over the general top plane of the structure while relative rotary movement is imparted as between the annulus and the supporting tables, and

20 means providing for pivotal movement of a car with respect to its wheels.

5. In an apparatus of the character described, inner and outer concentrically

spaced floor or table surfaces; a member bridging the space between said floor or table surfaces, a series of passenger cars having tongues, means on said bridging member to which said tongues are pivotally connected; and means for imparting a relative rotary movement between the anchorage and the 25 table.

6. In an amusement apparatus of the character described, concentrically arranged and spaced tables or floors provided with undulating surfaces on their tops; an annulus operatively fitting in the space between adjacent concentric edges of the tables; antifriction supports on which the annulus is rotatively mounted and by which it is guided; means for rotating the annulus; and passenger cars having tongues pivotally connected to the annulus, the cars having wheels designed to trail over the surfaces of said 30 tables and annulus when the latter is rotated.

In testimony whereof I affix my signature. 40
45 ERNEST KOHLER.
